(57) **CLAIM**

The ornamental design for a gun sight, as shown and described.

DESCRIPTION

FIG. 1 is a perspective view of a gun sight showing our new design;

FIG. 2 is another perspective view thereof;

FIG. 3 is a rear elevational view thereof, the appearance of the side opposite that shown in FIG. 3 being identical thereto;

FIG. 4 is a side elevational view thereof, the appearance of the side opposite that shown in FIG. 4 being identical thereto; and

FIG. 5, is a perspective views showing the gun sight in use;

FIG. 6, is another perspective views showing the gun sight in use; and,

FIG. 7, is another perspective views showing the gun sight in use.

[The material shown in broken lines forms no part of the claimed invention.] *The broken line showing of a shot gun in FIGS. 5, 6, and 7, is depicted for purposes of environment and forms no part of the claimed design.*

1 Claim, 2 Drawing Sheets

Matter enclosed in heavy brackets [ ] appears in the original patent but forms no part of this reissue; matter printed in italics indicates the additions made by reissue.
